UNITED STATES PATENT OFFICE.

HARRY G. OSBURN, OF DETROIT, MICHIGAN.

ELECTRIC IGNITION APPARATUS.

978,197.

Specification of Letters Patent. Patented Dec. 13, 1910.

Application filed October 1, 1908. Serial No. 455,592.

To all whom it may concern:
Be it known that I, HARRY G. OSBURN, a citizen of the United States, residing at Detroit, in the county of Wayne and State of Michigan, have invented new and useful Improvements in Electric Ignition Apparatus, of which the following is a full, clear, concise, and exact description, reference being had to the accompanying drawing, forming 10 a part of this specification.

This invention relates to improvements in electric ignition apparatus for explosive engines and the like, the principal object of the invention being economy in the use of current.

As electric ignition apparatus is usually arranged, if the engine happens to stop at a point at which the contacts of the mechanical timing device, which makes and 20 breaks the circuit in unison with the beats of the engine, remain in contact with each other, the current will continue to flow through the primary winding of the induction coil until such time as the engine is 25 started again or such time as a hand operated switch is opened. By the use of my invention, if the engine should stop at such a point that the contacts of the timing device are in contact with each other, the low- 30 resistance primary circuit is automatically opened by the action of a magnet which is provided for that purpose, the winding of this magnet having a resistance so high that even though the current continue to pass 35 through this winding for a considerable length of time no harm will be done, as the current which can pass through this winding will be comparatively small. Furthermore, in the ordinary running of the engine 40 the consumption of current is small when my improved apparatus is used because of the fact that the circuit through the primary winding of the induction coil is closed but once, and for an instant only, during 45 each cycle of the engine, if it be a single-cylinder engine, or once during each cycle of each cylinder in the case of a multi-cylinder engine.

In the accompanying drawing I have 50 shown a form of apparatus embodying my invention, the figure being of a diagrammatic nature.

Referring to the drawing, 10 is the core of the induction coil, 11 being the primary winding and 12 the secondary winding thereof. One terminal of the primary wind-

ing 11 is connected by means of wire 13 with one pole of the battery 14 and from the other pole of the battery leads a wire 15 to the contact 16 of a rotary timing device. 60 The cam 17 of the timing device is carried on a revolving shaft 18 and is so arranged that the circuit is closed through the timing device at the time when the charge in the cylinder of the engine should be ignited. 65 From the second contact 19 of the timing device leads a wire 20 to a circuit breaker which comprises an arm 21 pivoted between its ends at 22 and carrying an armature 23 upon one of its ends and another armature 70 24 upon its opposite end. The armature 23 is arranged to be attracted by the core 10 of the induction coil when current flows through the primary thereof. A spring 25 tends to swing the lever 21 about its pivot 22 75 in a direction to carry the armature 23 away from the core of the induction coil. The lever 21 carries a contact spring 26 which, when no current is passing, engages a contact such as a screw 27. The spring 25 is 80 secured to a screw or the like 28 to which the end of the wire 20 is connected, while the primary winding of the induction coil is similarly connected to the screw 27.

With the parts in the positions shown in the 85 figure the circuit which includes the primary winding of the coil, the battery, the timing device and the circuit breaker is open. When the cam of the timing device revolves to such a position as to close the contacts thereof together, this circuit is established and the 90 core of the induction coil draws the armature 23 to itself, thus breaking the circuit at the circuit breaker between the spring 26 and the point of the screw 27. With the ar- 95 rangement ordinarily employed heretofore, this breaking of the circuit would cause the armature to be drawn back from the core of the induction coil by the spring 25, whereupon the circuit would be re-established and 100 whereby a trembling or vibrating movement would be given to the armature and the circuit would be rapidly broken and re-established during the period in which the contacts of the mechanical timing device re- 105 mained in contact. This would result in a series of sparks being thrown between the contact points of the spark plug, whereas a single spark is all that is required to effect the ignition of the explosive mixture in the 110 cylinder of the engine.

In the system of apparatus illustrated in

the figure the reëstablishment of the circuit immediately after the breaking thereof by the movement of the armature toward the core of the coil is prevented. This result is accomplished by the provision of an electromagnet 28 which is arranged to exert its force upon the armature 24 carried by the lever 21. The winding of this magnet is connected at one end by means of the wire 29 with one pole of the battery 14, the opposite end of the winding being connected by means of the wire 30 with the wire 20 which leads from the contact 19 of the mechanical timing device. When the primary circuit is closed through the mechanical timing device, the battery, the primary winding of the coil and the contacts of the circuit breaker, a circuit is also completed through the timing device, the battery and the winding of the magnet 28. This magnet thereupon attracts the armature 24 to itself and continues to hold the same in its attracted position after the primary circuit has been broken by the separation of the contacts 26 and 27 of the circuit breaker, thereby preventing, for a time, reëstablishment of the primary circuit.

The winding of the magnet 28 has a resistance much greater than that of the primary circuit, so that if it should happen that the engine stops with the timing device in such position that its contacts are left closed, but a very small quantity of current would continue to pass through the magnet winding, this current being so small as to be practically of no account. In this way any practically objectionable waste of current is obviated, in case the contacts of the timing device remain in engagement with each other for an extended time. Furthermore, during the running of the engine, the circuit breaker is not permitted to vibrate as is the case in older forms of apparatus, but as soon as the primary circuit is "broken" the magnet 28

holds the contacts 26 and 27 apart and prevents the further passage of current through the induction coil until the contacts of the timing device have opened and thereby cut off the current from the magnet 28, thus permitting the contacts 26 and 27 to come together again.

Bridged across the contacts 26 and 27 is a condenser 31. One end of the secondary winding of the induction coil is also connected to one end of the condenser, the other end of this winding being connected by means of the wire 32 with one of the contacts of the spark plug 33. The other contact of the spark plug is connected by means of wire 34 with the wire 20, which leads to one of the contacts of the circuit breaker. This wiring system, as far as it relates to the secondary or sparking circuit, is well understood and requires no extended explanation.

Having thus described my invention, what I claim as new and desire to secure by Letters Patent, is:

The combination of a timing device; an induction coil in circuit therewith; a circuit breaker consisting of an arm pivoted between its ends and so disposed that one end can be attracted by said induction coil and a fixed contact engaging said arm when the latter is in its non-attracted position; and an electromagnet of high resistance arranged in operative relation with the other end of said arm to hold the circuit breaker open when it has been attracted by said induction coil.

In witness whereof, I have hereunto subscribed my name in the presence of two witnesses.

HARRY G. OSBURN.
